UNITED STATES PATENT OFFICE.

COLIN HUTCHINS, OF LEAMINGTON, ONTARIO, CANADA.

COLLAPSIBLE MOLD CORE.

Application filed November 1, 1924. Serial No. 747,208.

In my Patents Nos. 1,363,651 and 1,431,-
000, dated Dec. 28, 1920, and Oct. 3, 1922, re-
spectively, there are disclosed collapsible
mold cores that may be advantageously used
in a mold for producing hollow building
blocks made of concrete or other plastic ma-
terial, and this is an improvement in con-
nection with such collapsible cores.

My invention aims to provide a collapsi-
ble mold core somewhat along the lines of
the cores described in my prior patents, but
with the present core of such configuration
that it may be used in the formation of a
hollow wall. The core has mold plates or
frames adapted to be collapsed towards each
other and at all times maintained in a par-
allel relation. Adapted to be used with
the cores are centering members and spac-
ing devices, the latter forming covers for
the cores to prevent concrete or other plas-
tic material entering the cores during the
formation of a hollow wall.

My invention will be hereinafter specifi-
cally described and then claimed, and ref-
erence will now be had to the drawings,
wherein

Figure 1 is a perspective view of a collap-
sible mold core with one of the plates there-
of broken away;

Fig. 2 is an end view of the mold core in
a collapsed position;

Fig. 3 is a horizontal sectional view of
the mold core in distended position;

Fig. 4 is a vertical longitudinal sectional
view of the mold core taken on the line
IV—IV of Fig. 3;

Fig. 5 is a vertical sectional view of su-
perposed cores in molds adapted for produc-
ing a hollow wall, there being centering and
spacing members associated with the up-
permost core;

Fig. 6 is a perspective view of a com-
bined spacing member and cover for a core;

Fig. 7 is an end view of the spacing mem-
ber and cover on the core in the mold, and

Fig. 8 is a perspective view of a plurality
of mold cores with some of the cores partly
broken away.

Each collapsible mold core comprises a
set of rectangular frames 1 and 2 preferably
made of angle bars and riveted or otherwise
connected to some of the flanges of the angle
bar frames are mold plates 3. The frames
1 and 2 are in opposed relation and said
frames have the end flanges 4 thereof con-

nected by toggle levers 5 and links 6, the
links being pivotally connected to the tog-
gle levers 5, as at 7, so that the toggle con-
nections can be shifted upwardly to cause
the frames to move towards each other, as
best shown in Fig. 2.

To facilitate adjustment of the toggle
levers 5 the ends of said levers, at each end
of the core, are connected by bars 8 having
handles 9 at the upper ends thereof and in
addition to these bars is an intermediate
handle bar 10 pivotally connected by links
11 to a mid rail 12 of the frame 1; there
being a mid rail 13 for the frame 2 and for en-
gagement with the handle bar 10, so that
the links 11 may be placed transversely of
the collapsible core to press the center por-
tions of the mold 3 during the formation of
a wall.

The top rail 14 of the frame 1 has pivoted
latches 15 which may be swung over the
handles 9 and under the top rail 14 of the
frame 2 to hold the bars 8 in a lowered po-
sition, thus preventing accidental collapse
of the mold core when the core is lifted, and
more especially when elevated by gripping
the handles 9 at the ends of the core.

As shown in Fig. 5, collapsible cores may
be placed in interposed relation and in
spaced relation to outer panel mold mem-
bers 16 to permit of concrete 17 or other
plastic material being poured between the
mold plates 3 and the mold members 16 to
form a hollow wall or other structure.

In order that an upper core may be cor-
rectly positioned on a lower core centering
members 18 are employed, said members
having lower broad ends 19 fitting between
the adjoining rails of the superposed cores,
as best shown in Fig. 5. The upper ends 20
of the centering members are angular to ex-
tend on to one or the other of the top rails
of the upper core and with these centering
members in position the vertically disposed
cores will be properly alined with the mold 100
plates 3 flush for the formation of the inner
faces of a hollow wall.

In order that concrete or other plastic
material may be poured between the mold
members and about the cores, without en-
tering the cores, I provide a combined spa-
cing member and cover which is best shown
in Figs. 6 and 7. The cover is designated
20 and is in the form of an inverted channel
that may be fitted down over the upper end 110

of the core. Attached to the side flanges of the cover are U-shaped spacing members 21 and the members at each side of the cover are connected by handle rods 22. The spacing members are preferably made of a resilient material and can be sprung into position between the mold plates 3 and the mold members 16, thereby centering the core in the mold. Before the concrete completely hardens about the cores the spacing members 21 and the cover 20 are removed but the cores are left in position until the concrete has practically settled or been cured.

15 There may be instances where a hollow wall is to have its ends closed in which case there would be suitable end mold members and the endmost cores would be provided with vertical channel covers 23, as best 20 shown in Fig. 8, the covers preventing concrete from entering the endmost cores.

If the collapsible cores are of considerable depth and one placed upon the other suitable tools may be used for reaching through 25 the uppermost core to raise the handles in the lowermost core, or the upper core may be removed and then tools employed for extracting the lower core.

By reference to Figs. 1, 3, 4 and 8 it will 30 be noted that the mold plates 3 project beyond the frames and are slightly offset at one end of each core. In consequence of this the mold plates 3 of one core may overlap the mold plates of an adjacent core. 35 The offset edge of each mold plate is designated 24 and may be best observed in Fig. 8. With the mold plates 3 shiftable inwardly towards each other and in a common plane, it is obvious that a collapsed 40 core may be readily removed from a wall, furthermore, that by using the end covers 23 cores may be placed at an angle as would be necessary in the formation of an angular wall.

45 One embodiment of my invention has been illustrated but it is to be understood that the structural elements are susceptible to such variations and modifications as fall within the scope of the appended claims.

What I claim is:

1. A collapsible mold core comprising frames, plates attached to said frames, toggle links and levers connecting said frames so that said frames may be moved toward each other, hand bars to facilitate 55 actuating said links and levers, and latch mechanism for said hand bars to secure said core against accidental collapse, said mechanism being movable into and out of locking position when said mold is normally expanded by said links.

2. A collapsible mold core as called for in claim 1, wherein the last mentioned means includes latches carried by one frame and swingable over said handle bars and under a portion of the other frame.

3. Collapsible cores adapted to be placed one on the other in a mold, centering members suspended in the upper core and adapted to center the upper core relative to the 70 lower core, and a cover for the upper core extending over the upper ends of said spacing means.

4. Collapsible cores as called for in claim 3, and spacing members carried by said cover and adapted to engage the mold to center the cores relative to said mold, said members forming means for the removal of said cover.

5. Collapsible cores adapted to be placed one on the other in a mold, centering members suspended on the upper core and adapted to center the upper core relative to the lower core, and channel covers for the ends 80 of said cores.

6. The combination of superposed mold members, superposed cores in said superposed molds and adapted to cooperate therewith in the formation of a hollow wall, a centering member at the juncture of said 90 cores, and resilient spacing means for said cores yieldably engaging said molds.

7. The combination called for in claim 6, wherein a cover on the upper core supports 95 said resilient spacing means.

In testimony whereof I affix my signature.

COLIN HUTCHINS.
